UNITED STATES PATENT OFFICE.

EDWARD A. REED, OF OTTAWA, ILLINOIS.

CONVEYER.

1,158,848.

Specification of Letters Patent.

Patented Nov. 2, 1915.

Application filed November 5, 1914. Serial No. 870,328.

To all whom it may concern:

Be it known that I, EDWARD A. REED, a citizen of the United States, and a resident of Ottawa, in the county of La Salle and State of Illinois, have invented certain new and useful Improvements in Conveyers; and I do hereby declare that the following is a full, clear, and exact description thereof, reference being had to the accompanying drawings, and to the letters of reference marked thereon, which form a part of this specification.

This invention relates in particular to a portable conveyer outfit designed especially for unloading ears of corn or small grain in a crib, barn, car or the like. A conveyer of the type referred to comprises in general, an elevator adapted to receive the material at its lower end, raise the material and discharge it at its upper end into a horizontal drag or crib conveyer, the latter being located in and supported above the floor of the crib or barn. The material is discharged from the horizontal drag or crib conveyer into the crib, barn, car or other compartment provided to receive the same.

Among the objects of the invention is to improve the construction of the horizontal drag or crib conveyer in the several particulars as will hereinafter appear, and to provide in particular, means whereby the discharge opening of said horizontal drag or crib conveyer will be moved from one end of the conveyer to the other during the operation of the conveyer and thereby gain a uniform distribution of the material in the crib or other receptacle provided to receive the material. By moving the discharge opening of the horizontal drag or crib conveyer continuously from one end of the conveyer to the other during the operation of the conveyer, the material is discharged from the conveyer at a plurality of changing points, and the material is deposited on the floor of the crib or the like, in a layer of a uniform depth.

The invention consists further in matters hereinafter described and more particularly pointed out in the appended claims.

50 In the accompanying drawings illustrating my invention: Figure 1 is a view in perspective of a portable conveyer outfit of the kind referred to and showing the same in position along side of a crib with the horizontal drag or crib conveyer embodying the features of my invention located in a crib,

barn, or other receptacle provided to receive the material discharged. Fig. 2 is an enlarged longitudinal sectional view taken through the horizontal conveyer shown in Fig. 1; Fig. 3 is a transverse sectional view taken on line 3—3 of Fig. 2; Fig. 4 is a transverse sectional view taken on line 4—4 of Fig. 2; Fig. 5 is a fragmentary side elevational view of the conveyer showing the intermeshing driving gears at one end thereof; and Fig. 6 is a view in perspective of a portion of the movable bottom of the conveyer, the discharge opening in said bottom being shown.

Referring to the drawings, 10 indicates a horizontal drag or crib conveyer embodying the features of my invention. As shown in Fig. 1, the conveyer 10 is located in a corn crib or barn 11, which is adapted to receive the material discharged from said conveyer. Said conveyer 10 is horizontally arranged above, and preferably parallel to the floor of the crib or barn 11 and is suspended from the ceiling of the latter by suspension hooks 12 or other devices 12, 12. The material to be loaded in said crib or barn 11 is brought in from the field by a wagon or other like portable receptacle, 13. The material in said wagon 13 is dumped therefrom into an upwardly opening hopper 14 at the bottom of an elevator 15 which discharges at its upper end into said horizontal conveyer 10. As shown, the elevator 15 is located exterior to the crib 11. The upper end of said elevator extends into the crib in position to discharge into the conveyer 10 through a window opening or the like in the adjacent end wall of said crib. In the type of device shown in Fig. 1, the conveyer 10 is known as the horizontal drag or crib conveyer.

As shown in Figs. 2 to 4, both inclusive, the conveyer 10 comprises a pair of laterally spaced upright side walls 16, 16^a, preferably, equal in length and height. Extending between the side walls 16, 16^a at one end thereof is a shaft 17. Extending between said side walls 16, 16^a at the opposite end of the conveyer is a shaft 18. Extending between said side walls 16, 16^a between the shafts 17 and 18 and adjacent the former, is a shaft 19. Said shafts 17, 18 and 19 are parallel to each other and each of said shafts has its ends journaled in the side walls 16, 16^a of the conveyer.

Mounted on the shaft 17 between the side walls 16, 16^a is a pair of sprocket wheels

20, 20, the latter being secured to said shaft 17 so as to rotate therewith. As shown in the drawing, said sprocket wheels 20, 20 are secured to the shaft 17 by set screws or the like 21, 21.

5   Loosely mounted on the shaft 18 between the side walls 16, 16^a is a pair of sprocket wheels 22, 22, laterally spaced apart. Said sprocket wheels 22, 22 are equal in diameter to each other and to the sprocket wheels 20, 20 at the opposite end of the conveyer 10. Also loosely mounted on said shaft 18 between said sprocket wheels 22, 22 is a pair of sprocket wheels 23, 23, the latter being inside of the pair of sprocket wheels 22, 22. (See Fig. 4.) As shown in said Fig. 4, said shaft 18 is provided with reduced ends forming laterally, outwardly facing shoulders 24 against which the inner 10 small sprocket wheels bear. A washer on the like, 18^b, is interposed between each set of larger and smaller sprocket wheels 22, 23 respectively. The shoulders 24 prevent the adjacent set of larger and smaller sprocket 15 wheels from moving laterally inward. Lateral outward movement of said set of sprocket wheels is prevented by the adjacent side wall of the conveyer.

30   Mounted on the shaft 19 between said side walls 16, 16^a of the conveyer, is a pair of sprocket wheels 25, 25. Said sprocket wheels 25, 25 are fixed to the shaft 19 so as to rotate therewith. As shown in Figs. 2 and 3, said sprocket wheels 25, 25 are secured to the shaft 19 by set screws or the like, 26, 26. The sprocket wheels 23, 23 at one end of the conveyer and the sprocket wheels 25, 25 at the opposite end of the conveyer are each 35 equal in diameter, but all of said sprocket 40 wheels 23, 25 are smaller in diameter than the sprocket wheels 20, 22.

45   The pair of sprocket wheels 23, 23 at one end of the conveyer are in longitudinal alinement with the like pair of sprocket wheels 25, 25 at the opposite end of the conveyer. In other words, the smaller sprocket wheel at one end of the conveyer and adjacent the side wall 16, is in alinement 50 with the smaller sprocket wheel at the other end of the conveyer and adjacent the same said side wall 16. The same is true with respect to the smaller sprocket wheels adjacent the other side wall 16^a. The smaller sprocket wheels 23, 25 serve to operate an 55 endless conveyer member 27 which, as shown in the drawing, is of the slat or multi-scraper type. As shown, said conveyer 27 comprises a pair of endless chains 28, 28, one being trained over one set of longitudinally alined smaller sprocket wheels adjacent the side wall 16 of the conveyer 10, and the other chain is trained over the other set of longitudinally alined smaller sprocket wheels adjacent the side wall 16^a of the conveyer. Extending between and connected with said

chains 28, 28 at a plurality of longitudinally spaced points, are a plurality of flat scrapers or slats 29, 29. Said scrapers are rigidly connected with the chains 28, 28 by fastening screws 30, 30 inserted through inwardly extending ears or lugs 31, 31 on the inner sides of said chains 28, 28. See Figs. 3 and 4. The flat scrapers 29, 29 are preferably spaced equal distances apart and extend transversely across the conveyer chains 75 28, 28.

70   The larger sprocket wheels 20, 20 at one end of the conveyer are equal in diameter to each other and to the like larger sprocket wheels 22, 22 at the opposite end of the conveyer. The pair of larger sprocket wheels at one end of the conveyer are in longitudinal alinement with like sprocket wheels at the opposite end of the conveyer. Trained over said larger sprocket wheels is an endless member in the form of a belt 32 which extends between the side walls 16, 16^a of the conveyer 10 and incloses the slat or scraper conveyer 27 and its operating sprocket wheels 23, 25. In other words, the upper and lower laps of said endless belt 32 are above and below the upper and lower laps of the scraper conveyer 27. (See Fig. 2.) The lower lap of the endless belt 32 is below, but is arranged parallel to the lower lap of the conveyer 27 thereabove. The lower lap of said endless belt 32 or that portion of said belt which is always below the scraper conveyer 27, forms in effect a movable bottom for the conveyer 10 and serves 90 to support the material discharged thereinto during its progress toward the discharge opening in said belt. The material to be carried by the conveyer 10 is discharged into the same between the upper and 95 lower laps of said scraper conveyer 27 through one of the side walls of the conveyer by means of a spout 33. As shown in Figs. 2 and 3, said spout 33 extends into the 100 conveyer through an opening 34 made in the side wall 16^a. The endless belt 32 is provided with a plurality of discharge openings 105 35, 36. (See Fig. 2.)

110   The shafts 17 and 19 extend at one end beyond one of the side walls of the conveyer 10. As shown in the drawings, the shaft 17, 19 extend beyond the side member 16. Mounted on each shaft 17, 19 exterior to the side member 16, is a gear wheel 37, 38. Said gear wheels are equal in diameter 115 and are secured to the shafts 17, 19 so as to rotate therewith. The gear wheels 37, 38 mesh with each other so that the rotation of one will rotate the other. As said gear 120 wheels are equal in diameter, the shafts 17, 19 will be turned at the same rate of speed but in opposite directions. As a result, the endless scraper conveyer 27 and the endless belt 32 travel at the same rate of speed, but 125 in opposite directions. It follows, that the 130

endless scraper conveyer is moved in one direction while the endless belt 32 is moved in the opposite direction. The endless belt 32 is provided along its longitudinal margins with a plurality of equally spaced holes, 39, 39 as shown more clearly in Fig. 6. Said holes 39, 39 receive the sprocket teeth of the large sprocket wheels as the belt passes over the large sprocket wheels. 10 The endless belt 32 is moved upon the rotation of said large sprocket wheels.

For supporting the upper lap of the endless belt 32, side plates 40, 40 are secured by fastening members or bolts 41, 41 to the inner sides of the side walls 16, 16^a as clearly illustrated in Fig. 3. The upper lap of said endless belt 32 is adapted to slide along the upwardly facing surfaces of the said side plates 40, 40. For supporting the lower lap 20 of said endless belt 32, strips or bars 42, 42 are secured to the inner faces of the side walls, 16, 16^a below the lower lap of the endless belt. The lower lap of said endless belt 32 is adapted to slide on the upwardly facing surfaces of said bars 42, 42. The upper laps of the sprocket chains 28, 28 of the slat or scraper conveyer 27 are supported by strips or bars 43, 43 below such parts of said chains, while the lower laps of said 30 sprocket chains are supported by like strips or bars 44, 44 below such parts of said chains. Said supporting bars 43, 43 and 44, 44 are secured to the inner sides of said supporting plates 40, 40 as shown in Fig. 3.

35 The horizontal drag or crib conveyer 10 herein shown and described operates in the following manner: Ears of corn or grain to be deposited in the crib or barn 11 are dumped from the wagon or other portable receptacle 13 into the upwardly opening hopper 14 at the bottom or foot of the upwardly inclined elevator 15. Said elevator 15 is set in motion by rotating a main drive shaft 46, the latter being connected with 40 and rotated by any sort of a prime mover, such as a gas engine, or the like. The head shaft 47 at the upper end of the elevator is turned by moving the endless lift conveyer 45 in the elevator 15. Said head shaft 47 is 50 provided on its end extending exterior to the side of the elevator 15 with a sprocket wheel 48. A sprocket chain 49 transmits power from said sprocket wheel 48 on the head shaft 47 to the shaft 19 of the horizontal drag or crib conveyer 10. Said sprocket chain 49 is trained over a sprocket wheel 19^a 55 on said shaft 19 (see Fig. 3). In operating the elevator, the intermeshing gear wheels 37, 38 on the shaft 17, 19 of the horizontal drag or crib conveyer 10 are rotated, and as a result, the parts of the latter set in motion. As the elevator 15 is operated, the material emptied from the wagon 13 is raised to the top of the elevator and dumped 60 into the spout 33. The upper end of the ele-

70 vator 15 is so positioned as to discharge into said spout 33. The material emptied into the horizontal drag or crib conveyer 10 drops upon the lower lap of the endless belt 32 adjacent the shaft 19, and is carried over the lower lap of said belt toward the opposite end of the crib conveyer 10 by the scrapers 29, 29. The endless belt 32, as above stated, moves in a direction of the arrow shown in Fig. 2 or in other words, in a direction opposite or contrary to the direction of movement of the scraper conveyer 27, and when the parts are in positions shown in Fig. 2, the opening 35 in the endless belt 32 is below the lower lap of the endless scraper conveyer 27 and adjacent the shaft 18 at the farther end of said horizontal drag 10. The material carried forward by the scrapers 29, 29 is discharged from the drag 10 through said opening 35 80 as soon as the material is moved into such opening. The material discharged from the drag 10 falls upon the floor of the crib or barn 11, as is apparent. As the endless belt 32 moves, the discharge opening 35 travels 85 toward the shaft 17 at the nearest end of said drag 10, and the material emptied into the drag and carried toward the discharge opening 35 by the scrapers 29 is discharged from the drag at a plurality of 90 successive points along the length of the drag. In other words, the discharge opening constantly changing its position, the material is discharged from the drag 10 95 continuously, the point of discharge moving from one end of the drag to the other. When the discharge opening 35 reaches a point beyond the chute 33, the discharge opening 36 has been moved into position adjacent the shaft 18 and below the slat conveyer 27. In short, when one discharge opening in the endless member 32 moves out of discharging position at one end of the drag, another discharge opening moves into discharging position at the opposite 100 end of the conveyer. By moving the discharge opening from one end of the conveyer to the other, the material is deposited on the floor of the crib or barn 11 in a layer 105 of uniform depth, and the piling of the material in one pile of a thickness greater than another pile, is obviated. In other words, the horizontal drag or crib conveyer 10 constructed and described as herein shown, automatically effects an equal distribution of 110 the material in the crib or barn 11 without requiring the operator to manually move the discharge opening from one end of the drag to the other. After the drag or conveyer 10 is set in motion, the material is 115 discharged therefrom at a plurality of successive points along the length of the drag without requiring any attention being given thereto by the operator. 120

125 In horizontal drags or crib conveyers here- 130

tofore constructed and employed, the material was discharged from the drag through a discharge spout which could be moved manually from one end of the drag to the other. Often times, the material was allowed to pile up in one spot before the discharge spout was moved so as to start another pile in the crib. This resulted in piling the material in the crib in piles of unequal depths and in the case of ears of corn, the piles being of unequal depth, the corn at the bottom of the deepest pile could not be sufficiently dried and therefore, became decomposed and worthless. A careless operator could effect the loss of many ears of corn by failure to change the position of the discharge spout.

With a horizontal drag or crib conveyer embodying the features of my invention, an equal distribution of the material over the floor of the crib or bin is effected without requiring any attendance on the part of the operator. It follows, that the material will be deposited in the crib in a pile of equal depth throughout, so in the case ears of corn are being handled, the corn in one part of the crib will not be piled to such a height as to prevent the corn in the lower part of the pile from properly drying.

30 The endless belt 32 may be constructed in any suitable manner as long as the objects to be accomplished are performed. I have shown in the drawings, a preferred manner in which said endless belt 32 may be made.

35 As best shown in Fig. 6, the endless belt 32 comprises a plurality of flat metal plates, 50, 50, equal in width and length and flexibly connected at their meeting lateral edges, so that said plates will readily turn on a longitudinal axis as they pass around the sprocket wheels 20, 22. Said plates 50, 50 extend entirely across the endless belt 32 and are flexibly connected together by bending the adjacent lateral edges of the plates upwardly

40 into tubular form and inserting a pintle or rod 51 through the tubular parts thus formed. As shown in said Fig. 6, one plate 50 is provided along one of its lateral edges with tubular parts 52, 52 terminating short of the central portion of the plate. The next adjacent plate 50 is provided along its margin adjacent the tubular parts 52, 52 of the preceding plate, with a tubular portion 53, centrally disposed, and adapted to occupy the space between the tubular parts 52, 52 of the preceding plate 50. When the tubular parts of the plates are in alinement, as

45 shown in Fig. 6, the pintle or rod 51 is inserted through such parts so as to pivotally connect the plates 50, 50 together. Each plate 50 is so constructed and flexibly connected with its adjacent plates 50, 50 in the manner described. At the discharge opening formed in the endless belt 32, the plates 50 at each side of the discharge opening are

spaced apart a sufficient distance to provide the discharge opening. Said plates 50, 50 are connected with each other at their marginal portions by relatively short flat plates, 55, 55 on each side of the discharge opening. Said short sections 55, 55 are provided along their meeting edges with alined tubular portions 56, 57 formed by bending the lateral margins of the plates in a tubular form. One tubular portion 56, 57 is on one short plate and the other tubular portion is on the other plate. A short pintle or rod 58 is inserted through the alined tubular portions of the short plates 55, 55, so as to pivotally connect the latter together. As shown in Fig. 6, the holes 39, 39 for the sprocket teeth are formed in the plates of which the endless belt 32 is constructed. It is, of course, to be understood, that the endless belt 32 may be made in any suitable manner and any suitable means may be employed for driving the same simultaneously with the scraper or like conveyer 27.

The lower lap of the flexible member 32, or that portion of the endless belt 32 which is always below the lower lap of the scraper chain 27, constitutes in effect the bottom of the horizontal drag or crib conveyer 10. As the endless belt moves, the drag 10 is provided with a movable bottom. The discharge opening being in the movable bottom, the drag 10 is provided with a movable discharge opening, or as may be expressed, with a movable bottom having a discharge opening therein.

In Fig. 2 I have shown ears of corn 59, 59 being moved over the movable bottom of the drag 10 by the flat upright scrapers or slats 29, 29.

Although I have shown my invention as applied to the horizontal drag or crib conveyer of a portable corn or small grain conveyer outfit, it is to be of course understood, that I may apply the features of my invention to any type of conveyer wherein an equal distribution of material over the floor of the compartment or receptacle is desired.

A device herein described and shown in detail, although embodying the features of my invention, may be variously modified with regard to its details of construction and arrangement of parts and I do not desire to be limited to the specific features illustrated and described, except in so far as pointed out in the annexed claims.

I claim as my invention:

1. A conveyer, comprising side walls, and a bottom wall adapted to be moved endwise of the conveyer, said bottom wall being provided with a discharge opening adapted to be moved from one end of the conveyer to the other in the endwise movement of said bottom wall, means for moving the material, deposited on said bottom wall, toward said

discharge opening, and mechanism connecting said means with said bottom wall whereby the former and the latter will be moved simultaneously.

- 5 2. A conveyer, comprising side walls, an endless belt located between said side walls and having a portion extending along the bottom of the conveyer and forming a movable bottom for the same, said belt being 10 provided with a discharge opening adapted to be moved from one end of the conveyer to the other in the movement of said belt, means for moving the material, deposited on the portion of said belt forming the movable 15 bottom, toward said discharge opening, and mechanism connecting said means with said belt whereby the former and the latter will be moved simultaneously and in opposite directions.
- 20 3. A conveyer, comprising side walls, an endless belt located between said side walls and having a portion extending along the bottom of the conveyer and forming a movable bottom for the same, said belt being 25 provided with a discharge opening adapted to be moved along the bottom of the conveyer from one end thereof to the other in the movement of said belt, an endless member embracing means acting to move the material, deposited on the portion of the belt forming the movable bottom, toward said discharge opening, and mechanism connecting said belt with said endless member whereby the former and the latter will be 30 moved simultaneously and in opposite directions.
- 35 4. A conveyer, comprising side walls, an endless belt located between said side walls and having a portion extending along the bottom of the conveyer and forming a movable bottom for the same, said belt being provided with a discharge opening adapted to be moved along the bottom of the conveyer from one end thereof to the other in the movement of said belt, an endless member trained over and moved by the rotary members on the intermediate shaft and the shaft at the opposite end of the conveyer, a plurality of scrapers or slats secured to said endless member and adapted to move the material, deposited in the lower lap of the belt, toward said discharge opening, and mechanism connecting said intermediate shaft with the adjacent end shaft whereby said belt and said endless member will be moved simultaneously and in opposite directions.
- 40 5. A conveyer, comprising side walls, an endless belt located between said side walls and having a portion extending along the bottom of the conveyer and forming a movable bottom for the same, said belt being provided with a discharge opening adapted to be moved along the bottom of the conveyer from one end thereof to the other in the movement of said belt, an endless member embracing a plurality of scrapers or slats adapted to move the material, deposited on the portion of the belt forming the movable bottom, toward said discharge opening, and mechanism connecting said belt with said endless member whereby the former and the latter will be moved simultaneously and in opposite directions.
- 45 50 55 60 65 70 75 80 85 90 95 100
- the side walls; there being one shaft adjacent each end of the conveyer, a rotary member mounted on each of said shafts, an endless belt trained over and moved by said rotary members and having a portion thereof extending along the bottom of the conveyer and forming a movable bottom for the same, said belt being provided with a discharge opening, adapted in the movement of the belt to be moved along the bottom of the conveyer from one end thereof to the other, an endless member located in said conveyer for moving the material, deposited on the movable bottom, toward said discharge opening, and mechanism connecting said belt with said endless member whereby the latter and the former will be moved simultaneously and in opposite directions.
6. A conveyer, comprising side walls, shafts extending between and journaled in said side walls; there being a shaft adjacent each end of the conveyer and a shaft intermediate the first mentioned shafts, rotary members mounted on each of said shafts, an endless belt trained over and moved by the rotary members mounted on the shafts at the opposite end of the conveyer; one of the laps of said belt extending along the bottom of the conveyer and forming a movable bottom for the same, said endless belt being provided with a discharge opening adapted to be moved along the bottom of the conveyer from one end thereof to the other in the movement of said belt, an endless member trained over and moved by the rotary members on the intermediate shaft and the shaft at the opposite end of the conveyer, a plurality of scrapers or slats secured to said endless member and adapted to move the material, deposited in the lower lap of the belt, toward said discharge opening, and mechanism connecting said intermediate shaft with the adjacent end shaft whereby said belt and said endless member will be moved simultaneously and in opposite directions.

In testimony, that I, do claim the foregoing as my own invention and affix my own signature in the presence of witnesses, this second day of November A. D. 1914.

EDWARD A. REED.
